[57] CLAIM

The ornamental design for a combined container and applicator for hair gel, as shown and described.

DESCRIPTION

FIG. 1 is a top perspective view of a combined container and applicator for hair gel;

FIG. 2 is a front elevational view thereof, the side opposite being identical to the side shown;

FIG. 3 is side elevational view thereof, the side opposite being identical to the side shown;

FIG. 4 is a top plan view thereof;

FIG. 5 is a bottom plan view thereof;

FIG. 6 is an exploded front elevational view thereof;

FIG. 7 is an exploded perspective view thereof;

FIG. 8 is a top plan view of the container portion shown separately for clarity of illustration; and,

FIG. 9 is a top plan view representing a modified embodiment of the design of FIGS. 1-8 with undisclosed portions of this modified embodiment being identical to those of the first disclosed embodiment.
